DESIGN FOR A COMBINED HAIRPIN HOLDER
AND OPENING FIXTURE

John A. Bennett, Tulsa, Okla.

Application September 29, 1947, Serial No. 141,653

Term of patent 14 years

(Cl. D86—10)

To all whom it may concern:

Be it known that I, John A. Bennett, a citizen of the United States, residing at Tulsa, Oklahoma, in the county of Tulsa and State of Oklahoma, have invented a new, original, and ornamental Design for a Combined Hairpin Holder and Opening Fixture, of which the following is a specification, reference being had to the accompanying drawing, forming a part thereof.

Fig. 2 is a front elevational view thereof,

Fig. 3 is a side elevational view thereof; and

Fig. 4 is a plan view thereof.

I claim:

The ornamental design for a combined hairpin holder and opening fixture, as shown.

JOHN A. BENNETT.
